(57) **CLAIM**

The ornamental design for a lid for beverage container as
shown and described.

DESCRIPTION

FIG. 1 is a top rear perspective view of the lid for beverage
container, according to the new design.

FIG. 2 is a bottom rear perspective view of the lid for
beverage container shown in FIG. 1.

FIG. 3 is a top front perspective view of the lid for beverage
container shown in FIG. 1.

FIG. 4 is a bottom front perspective view of the lid for
beverage container shown in FIG. 1.

FIG. 5 is a rear elevation view of the lid for beverage
container shown in FIG. 1.

FIG. 6 is a front elevation view of the lid for beverage
container shown in FIG. 1.

FIG. 7 is a right side elevation view of the lid for beverage
container shown in FIG. 1.

FIG. 8 is a left side elevation view of the lid for beverage
container shown in FIG. 1.

FIG. 9 is a top plan view of the lid for beverage container
shown in FIG. 1; and,

FIG. 10 is a bottom plan view of the lid for beverage
container shown in FIG. 1.

The broken lines in the drawings illustrate portions of the lid
for beverage container that form no part of the claimed
design.
